SHOE POLISHING MACHINE OR THE LIKE

Egon Dreibholz, Wuppertal-Barmen, Germany, assignor to Firma Frobana KG., Wuppertal, Germany, a corporation of Germany

Filed Apr. 22, 1965, Ser. No. 84,928

Term of patent 14 years

(Cl. D9—2)

The figure is a perspective front view of a shoe polishing machine or the like, showing my new design.

The side not shown is like the side shown. The rear not shown is flat and unornamented.

The dominant features of my design reside in the portions shown in full lines.

I claim:

The ornamental design for a shoe polishing machine or the like, as shown and described.
